UNITED STATES PATENT OFFICE.

THEODORE KISOR, OF GENEVA, NEW YORK, ASSIGNOR TO ROLL-O MANUFACTURING COMPANY, INC., OF GENEVA, NEW YORK, A CORPORATION OF NEW YORK.

BASEBALL-GAME APPARATUS.

Application filed March 2, 1922. Serial No. 540,530.

To all whom it may concern:

Be it known that I, THEODORE KISOR, a citizen of the United States, and resident of Geneva, in the county of Ontario and State 5 of New York, have invented certain new and useful Improvements in a Baseball-Game Apparatus, of which the following is a specification.

The present invention relates to a base-10 ball game apparatus and has for its object to provide means by which a game may be played closely resembling and simulating an actual game of professional baseball, and not depending solely upon chance, but per-15 mitting a player with a knowledge of the professional game to use such knowledge for the purpose of increasing his opportuni-20 ties for winning the game.

To this and other ends, the invention con-25 sists of certain parts and combinations of parts, all of which will be hereinafter de-30 scribed, the novel features being pointed out in the appended claims.

In the drawings:

Fig. 1 is a plan view of a game board constructed in accordance with this invention with charts thereon;

Fig. 2 is a side view of one of the bodies or men used in the game;

Figs. 3 to 5, inclusive, are perspective views of three cubes forming one embodiment of the chance devices used in the game; and

Fig. 6 is a plan view of a portion of another embodiment of the invention in which the chance devices and the charts are combined.

Referring more particularly to the drawings, 1 indicates a board having printed or otherwise delineated thereon a field or diamond similar to an ordinary baseball field or diamond with a home base 2, first base 3, second base 4, and a third base 5 and with or without any other matter or marking 45 which will tend to simulate an ordinary baseball field.

It is preferred to employ in connection with the field or diamond, a plurality of movable bodies 6 of which there may be 50 any desired number, eighteen in this instance, for representing the men or two teams of nine each, as in an ordinary baseball game, these men, when not being used, being fitted, if desired, in pockets 7 ar-55 ranged in two rows of nine each on opposite

sides of the names of the men which may correspond to names of men in the big baseball leagues, as indicated at 10.

There may also be provided a score keeping means, which, in this instance, is com-60 bined with the board 1 and, to this end, the latter may be provided with suitably designated spaces 11 for keeping the score by innings, and adjacent these spaces may be arranged a suitably numbered pocket 12 for 65 receiving a marker held, when not in use, in a pocket 13 and adapted to indicate the number of players out in any inning. The board may also have suitably designated pockets 14 in which a marker, normally 70 held in the pocket 15, may be fitted to indicate the number of balls against a man. There may also be provided suitably designated pockets 16 for receiving a marker, 75 normally held in the pocket 17, for indicating the number of strikes against a man. The board may also be provided with suitably designated pockets 18 for receiving a marker, normally held in a pocket 19, for indicating the number of runs made by any 80 team during one inning.

In order that the batter body may be held in position at the home plate and the men on bases may be suitably positioned on such bases, the home plate as well as the first, 85 second and third bases are provided with pockets, indicated at 20, 21, 22 and 23 respectively into which the reduced ends 8 of the men or bodies 6 may be fitted. Adjacent the first, second and third bases, pock-90 ets 24, 25 and 26 may be provided, respectively, for giving advanced positions of the men or bodies at such bases to be used in a manner to be described more particularly hereinafter.

In order to determine the result of a pitched ball with respect to the body or man representing the batter, as well as to determine whether any men on the bases are to advance, there is provided a main chart 100 which, in the embodiment shown in Fig. 1, comprises a plurality of main divisions, 6 in this instance, 27, 28, 29, 30, 31 and 32, each main division having sub-divisions, 11 in this instance, indicated at 33, 34, 35, 36, 37, 38, 39, 40, 41, 42 and 43, this chart, in the embodiment shown in Fig. 1, being provided on the board 1 beyond the playing field. The main divisions are distinguished by one type of characters as letters A, B, 110

C, D, E and F, while the sub-divisions are distinguished by a different type of characters, as numbers 2 to 12 inclusive. Each sub-division sets forth the result on the 5 batter of a ball thrown by the pitcher to the batter and, in some instances, affects the positions of men on bases and this result is indicated either on the score board or by the shifting of the position of the batter and 10 the men on the bases.

Another or selective chart is provided for determining the result of a pitched ball to the batter with respect to a body or man representing the batter and also in every 15 instance with respect to a body or bodies representing a man or men on the bases. This chart is also preferably divided into six main divisions indicated at 44, 45, 46, 47, 48 and 49 and distinguished by letters A 20 to F inclusive, each of these main divisions is sub-divided to provide a plurality of sub-divisions indicated at 50, 51, 52 and 53. This chart is used only on selection by the player before the use of chance devices as, 25 for instance, like those to be described, the selection being made preferably by moving the man or men on the bases 3, 4 and 5 to the advanced positions 24, 25 and 26 before the use of such chance devices.

30 The chance devices illustrated in Figs. 3, 4 and 5 embody three cubes indicated at 54, 56 and 56. The cube 54 has its six sides provided with the letters A to F, inclusive, the same as the characters distinguishing the 35 divisions of the main chart, while the cubes 56 are duplicates of each other and have their six faces provided with the numbers 1 to 6, inclusive. When the main chart containing the divisions 27 to 32 is to be used, 40 the uppermost faces of the cube 54 will indicate the main division of the chart on which the result is to be read, while the sum of the uppermost faces of the two cubes 56 will indicate the sub-division of the main division 45 to be used for determining the result. This result is then noted on the board by re-positioning the men on the board and indicating the results on the score board if necessary. Should it be desired to use the chart 50 having the main divisions 44 to 49 inclusive, then the cube 54 alone is used and, at the same time, the men on the bases are moved to the advanced positions 24, 25 or 26 or any one of all said positions. Of course, 55 this selection throw is only made when men are on the bases and that sub-division of the main division 44 to 49 is used which is most appropriate to the position of such men on the bases, the matter in the sub- 60 divisions in the main divisions 44 to 49 being such that only one of such sub-divisions will be applicable to the positions of the men on the bases.

In Fig. 6 the chance devices and the charts 55 are combined and, when this structure is

used, the board will not be provided with the chart, but may otherwise be the same as that shown in Fig. 1. In the embodiment shown in Fig. 6, a disk or plate 57 is employed and this disk or plate has a main 70 chart formed by main divisions 27^a to 32^a, inclusive, which are the same as the main divisions on the chart illustrated in Fig. 1. There is also employed a selective chart having sub-divisions 44^a to 49^a which also 75 has sub-divisions the same as the selective chart formed by main divisions 44 to 49 of Fig. 1.

The chance devices of the embodiment shown in Fig. 6 may employ a rotary member 58 pivoted at 59 to the center of the disk and having two pointers or indicators 60 and 61. The indicator 60 is adapted to operate over an annular series of numbers 62 concentric with the turning axis 59 and separated by lines 63 into a number of different divisions corresponding to the divisions of the two charts, each of these divisions being divided by lines 64 into sub-divisions corresponding to the sub-divisions of the main divisions 27^a to 32^a, the numbers 62 of the sub-divisions of the chance devices corresponding to the numbers of the sub-divisions of the main divisions 27^a to 32^a and each 90 main division of the chance devices being distinguished by characters, such as the letters 65, which also serve for distinguishing the main divisions 27^a to 32^a of the chart. The indicator 60 is used to determine the result of a pitched ball with respect to the 95 body or man representing the batter as well as the position of any men on bases. The indicator 61 operates over the sub-divisions 44^a to 49^a of the elective chart, the letters 66 designating said chart also acting to point out through said indicator the main division of the elective chart to be used.

In the use of the embodiment shown in Fig. 6, a player spins the indicating member 58 and unless a selection is made previous to said spinning by the advancement of the men on the bases to the advanced positions 24, 25 and 26, then the player takes the result of the indicator 60, which, cooperating with the annular series of numbers 62, will point out one number on one of the main divisions of the main chart and this number will in turn point out on the sub-division of the main divisions 27^a to 32^a, the result of the play. Should the player advance a man or men on bases to any one or more of the advanced positions 24 to 26, then he must follow the result pointed out by the indicator 61 on the most appropriate sub-division of the main divisions 44^a to 49^a of the elective chart.

From the foregoing it will be seen that there has been provided an improved game apparatus designed for playing a game closely resembling and simulating an actual 130

game of professional baseball. This apparatus provides for any contingency that might occur in an actual game. It permits the player to put himself in the position of a captain or manager of a team and through the selective chart to exercise individual judgment based upon the position of the men on bases or the status of the game and of the score, so as to overcome the results of the chance devices upon the batter alone. It has been found that a player with a good knowledge of the professional baseball game can, through the selective chart, defeat a player who is not so well informed. The game apparatus can be used by the manager of a professional team to illustrate and instruct his players in judgment in individual and team play. The sub-divisions of the chart are so arranged that games are rarely found with more than the low score of a good game and in many instances games of more than the usual number of innings with low scores are frequent, thus increasing interest as the game proceeds and creating much excitement.

What I claim as my invention and desire to secure by Letters Patent is:

1. A game apparatus comprising a member provided with means representing a baseball field, a plurality of bodies adapted to be moved around the field in simulation of the plays in baseball, a chart having a plurality of main divisions, each main division having a plurality of sub-divisions embracing a plurality of designations of plays, and a selective chart having a plurality of main divisions each embracing a plurality of designations of plays under different situations of the player, chance controlled means having indicia associated with the main divisions of both of said charts and indicia associated with the sub-division of the main divisions of the first mentioned chart.

2. A game apparatus comprising a game board provided with means representing a baseball field including the bases, diamond and out field and having adjacent to each of its three bases advance positions, a plurality of bodies adapted to be moved around the diamond in simulation of plays in baseball, a chart having a plurality of main divisions, each main division having a plurality of sub-divisions for ascertaining the result of a pitched ball on the batter and on the positions of men on the bases, indicia associated with the main divisions and also with the sub-divisions, a selective chart having a plurality of main divisions for ascertaining the result of a pitched ball on the batter also as well as the bodies shifted to advance positions, indicia associated with each of the main divisions of the selective chart, and chance devices having indicia cor-

responding to the indicia associated with both charts.

3. A game apparatus comprising a member having means representing a baseball field including the bases, diamond and out field, a plurality of bodies adapted to be moved around the diamond in simulation of the plays in baseball, a chart having main divisions and sub-divisions under the main divisions, the main divisions being distinguished by a different type of characters than the sub-divisions, the characters distinguishing the main divisions being all different and the characters distinguishing the sub-divisions being the same in all main divisions, and chance devices having characters corresponding to the characters associated with said chart and permitting the selection of plays from said chart.

4. A game apparatus comprising a member provided with means representing a baseball field, including the bases, diamond and out field, a plurality of bodies adapted to be moved around the diamond in simulation of the plays in baseball, a main chart having main divisions and subdivisions under the main divisions, the main divisions being distinguished by a different type of characters than the subdivisions, the characters distinguishing the main divisions being all different and the characters distinguishing the subdivisions being the same in all main divisions, a selective chart having main divisions with distinguishing characters and subdivisions under each main division provided with such matter that only one such subdivision will be applicable to the position of the men or bodies, and chance devices having characters corresponding to the characters associated with the charts, said chance devices employed in connection with the chart having selective means for pointing out the main divisions of the selective chart.

5. A game apparatus comprising a game board having means thereon for indicating different positions, a body adapted to be moved to such different positions on the board, means for indicating the movement of the bodies to the positions, said means comprising a chart having main divisions and subdivisions under the main divisions, the main divisions being distinguished by a different type of characters than the subdivisions, the characters distinguishing the main divisions being all different and the characters distinguishing the subdivisions being the same in all main divisions, and chance devices having characters corresponding to the characters associated with the chart to permit a selection of plays from the chart.

THEODORE KISOR.
